BUTTER CARTON

Lawrence S. Wysocki, Chicago, Ill., assignor to Hoerner-Waldorf Corporation, St. Paul, Minn., a corporation of Delaware

Filed Nov. 30, 1966, Ser. No. 598,643
10 Claims. (Cl. 99—179)

This invention relates to a butter carton or the like having an easy opening device, the cartons being particularly adapted for use with a product in the form of individual sticks or quarters.

Conventional cartons are designed to accommodate a pound of butter in the form of a solid block or in the form of quarters or sticks. When quarters are used, the individual sticks of butter may be arranged in a row or be placed in paired layers. In some instances these cartons may be provided with an easy opener in the form of overlying flap portions which may be separated to expose the product. It is an object of the present invention to provide an easy opener arranged along overlying closure panels of the carton whereby at least the end of one of the quarters will be exposed when the opener is removed.

It is a further object of the present invention to provide an opener comprising adhered closure flaps having a series of perforations along the fold lines connecting the flaps to similar top and bottom panels of the carton, whereby partially opening the flaps will expose at least one stick of the product in the carton.

For one form of butter or margarine carton, the sticks of the product are generally square in cross-section, being approximately 1 1/4" x 1 1/4" and approximately 5" long. The generally rectangular similar carton top and bottom panels are of a slightly greater length and slightly greater combined total width than the sticks of the product. The top and bottom panels are hingedly connected to a back or first panel. Hingedly connected side and front closure panels are provided from both top and bottom panels to close the sides and front of the carton when the closure panels are folded into overlying relation and secured.

Angularly connected cuts are provided along one or both hinged connections of the side closure panels to the top and bottom panels, or alternatively angular cuts are provided along one hinge line with perforations along the other hinge line. A tab or lip may be provided at the ends of the side closure panels, the tabs extending in registered relation to provide a grasping lip. By lifting upwardly on the lip portion, the side closure panels are separated from the top and bottom panels along the lines of perforation or cuts to expose the product.

In the preferred construction, a pair of registered transverse fold lines extend across the side closure panels, the weakened lines of separation in the form of the perforations or cuts terminating at these transverse lines.

A particular advantage of the present device lies in the fact that the angled cuts do not fuse together readily when heat is applied to the side closure panels in the final sealing. Such fusing constitutes a problem with straight perforations. In the preferred construction, the angularly connected cuts are arranged at a 45° angle with a 50% cut score line being provided along the base of the angled cuts. The leading cuts or nicks terminate on or adjacent to the edge of the lip. Accordingly, opening of the carton so that the contents of the carton may be dispensed is readily accomplished. It will be understood that the angled cuts may be used in both main closure panels, or the angled cuts may be used in combination with a standard perforating rule.

These and other objects will be more fully detailed and set out in the accompanying specifications when taken in conjunction with the drawings herein in which:

2

FIGURE 1 is a plan view of the carton blank of the present invention illustrating one form of easy opening device.

5 FIGURE 2 is a perspective view of an erected and sealed carton illustrating my easy opening device.

FIGURE 3 is a perspective view of an opened carton.

FIGURE 4 is a view of the portion of the blank from which the carton of FIGURE 3 is formed.

10 FIGURE 5 is a view of the blank in which angular cuts are provided along both hinge lines.

FIGURE 6 is a view of the blank from which the carton of FIGURE 3 is made.

FIGURE 7 is a view of the carton of FIGURE 1 prior to closing of the main closure flaps.

FIGURE 8 is a view of a partially folded blank particularly illustrating the lip portion of the easy opener.

FIGURE 9 is a view of the carton of FIGURE 7 prior to the closing of the main closure flaps.

20 FIGURE 10 is a diagrammatic view illustrating the side by side relationship of sticks of butter or margarine in a carton in relation to the closure panels of the easy opener.

The drawings illustrate a butter or margarine carton A formed from a blank such as B in one form of construction.

25 A modified form of construction is labeled C and is illustrated in FIGURE 5.

My construction is particularly designed to accommodate a plurality of sticks of a product arranged in side by side relationship such as is normally utilized for butter, 30 margarine and the like.

Such cartons generally provide a pair of opposed generally rectangular similar top and bottom panels 10 and 12 respectively hinged along opposed edges by parallel 35 fold lines 14 and 16 to a back panel or first panel 18.

Front closure panels which may be referred to as second and third panels 20 and 22 of a cross-sectional size corresponding generally to the back panel 18 are provided, the panels 20 and 22 being connected to the edge of one 40 of the top and bottom panels 10 and 12 along fold lines 24 and 26 and foldable into face contact to provide a tubular body with panels 10, 12, and 18. Closure panels 28 and 30 are hingedly connected along a fold line 36 to the top and bottom panels 10 and 12. Main closure panels 32 and 34 are hingedly connected along fold line 45 38 which may be a cut score line to the top and bottom panels 10 and 12.

A pair of end closure flaps 40 and 42 are hingedly connected to the back panel 18 along parallel fold lines 38 and 36, the end flaps 40 and 42 being separated from the 50 closure panels by cut lines 44, 46, 48 and 50. The cut lines 48 and 50 are arcuate convexly with the ends of the cut lines terminating along extensions of the fold lines 14 and 16 to provide lip portions 52 and 54 extending at their intermediate portions beyond the fold lines 14 and 16.

Closure panel 20 is provided with a pair of end flaps 56 and 58 connected to the closure panel 20 along the parallel hinge lines 36 and 38.

60 Portions of the end flaps 56 and 58 may be notched as indicated at 60 and 62 along cut lines 64 and 66 which separate the flaps 56 and 58 from the side closure panels 30 and 34.

65 The pair of adjacent closure panels 32 and 34 designated as main closure panels are provided with weakened lines of separation extending along the hinge line 38 to enable the closure flaps 32 and 34 to be at least partially separated readily from the erected carton A. The weakened lines of separation illustrated in FIGURE 1 are in the form of perforations 60 and angled cuts or diagonals 62 which extend into the mediate portion of the 70 panels from a point adjacent the fold lines. The weakened

lines of separation 60 and 62 preferably extend from an end of the lips 52 and 54 to a point terminating short of the other end of the flaps 32 and 34. Transverse fold lines 64 and 66 are provided at the point of termination of the weakened lines of separation 60 and 62.

In erection, the top and bottom panels 19 and 12 are folded into parallel relation substantially normal to the back panel 18. The panel 22 is folded to a position substantially parallel to the back panel 18 with the front closure panel 20 folded into overlying relationship thereto. End flaps 56 and 58 are folded inwardly with side closure panels 28 and 30 folded into overlying relationship to the end flaps 56 and 58.

End flaps 40 and 42 are folded into the position illustrated in FIGURE 7, and then the main closure flaps 32 and 34 are then folded into overlying relation and sealed. As may be observed in FIGURES 9 and 10, the lip portions 52 and 54 extend beyond the end of the carton to provide a grasping portion.

The blank B illustrated in FIGURE 1 is furnished to the product manufacturer with the panels 20 and 22 adhered together in overlying relation. The carton is squared, the product inserted, and the side closure flaps adhered in overlying relation as previously described. FIGURE 8 illustrates such a glued blank as furnished to the product manufacturer.

As may be seen in FIGURE 3, when the main closure flaps are raised, one or more quarters of the product are exposed. The main closure flaps separate from the top and bottom panels along the weakened lines of separation and fold into an upright position as indicated in FIGURE 3 along the transverse fold lines which have been previously described. In this position, the sticks of the product may be easily removed from the carton.

I have found that the separation of the main closure panels from the top and bottom panels may be more easily accomplished by providing a substantially 50% cut score at the base of the cutting arrangement, as best illustrated in FIGURES 1 and 4. This cut score line has been designated with the numeral 68. Similar cut score lines have been designated with the same numeral in FIGURES 4, 5, and 6.

In preferred construction, the angled cuts are an angle of 45°, and these cuts combined with the cut score at the ends of the diagonally cut lines enable the carton to be readily opened.

As has been indicated, the angled cuts in the form of diagonal lines may be used in both main closure panels or in combination with a standard perforating rule as indicated in FIGURE 1. FIGURE 5 illustrates the modified construction in which the angled cutting is used in both main closure panels. While these panels are of the general shape of the panels previously described, they have been provided with the numerals 70 and 72 to distinguish the modified construction.

It will be understood, that the cut score at adjacent the ends of the diagonal cut lines enables the carton to be more readily opened.

The panel 20 may be of slightly less width than the panel 22 which it overlies. The panel 22 is of substantially the same width as the rear panel 18, whereas the panel 20 is sealed or adhered to the panel 22 in the erected carton and accordingly no necessity exists for the panel 22 correspondent with the panel 18.

In the preferred construction the angled cuts intermediate the ends are 100% cuts while the cut score 68 is a 50% cut score. The juncture of connecting of angled cuts at this apex is approximately $\frac{1}{8}$ " above the cut score lines.

The lead nick 74 indicated in FIGURE 4 is approximately .028 whereas the other nicks 76 are approximately .014 in the preferred construction as distinguished from the 100% cut score of the intermediate portion of the diagonal cut score lines.

It has been found that on heat sealable butter cartons

such as are described, that the standard perforating rule tends to fuse together when heat is applied in the final sealing. The angled cuts do not fuse together so readily when heat is applied and consequently the opener functions efficiently whether provided along one or both sides of the main closure panels being provided with the angled cutting arrangement.

It will be apparent that the main closure panels will tend to separate from the carton along the weakened lines of separation. It is apparent, the carton is readily opened with the sticks of the product in dispensing relation to the opening. If desired, the opener may be opened only the width desired to permit one stick of the product to be exposed.

As may be seen in FIGURE 2, the grasping lips 48 and 50 extend perhaps $\frac{1}{8}$ " beyond the panel 20 which serves to provide a sufficient surface to enable the easy opening main panels to be readily grasped and lifted, but without interfering with the normal packing of the cartons in an outer carton.

As is illustrated in FIGURE 3, the main closure panels have separated from the carton A along the angled cuts 76.

In accordance with the patent statutes, I have described the principles of construction and operation of my easy opening device; and while I have endeavored to set forth the best embodiment thereof, I desire to have it understood that obvious changes may be made within the following claims without departing from the spirit of my invention.

I claim:

1. A butter carton or the like comprising:
a pair of similar rectangular main panels,
a first side panel hingedly connecting opposed edges of
said main panels,
second and third side panels each hingedly connected
to the edge of one of said main panels parallel to said
opposed edges and folded into face contact to pro-
vide a tubular body,
said second side panel lying outwardly of said third
side wall panel,
closure flaps hingedly connected to said first and sec-
ond side wall panels and folded in coplanar relation,
closure flaps on said main panels folded to overlie said
side wall closure flaps and secured together in face
contact,
registered fold lines extending across said main panel
closure flaps normal to the lines of fold connecting
said last named closure flaps to said main panels
and spaced from said first side panel a distance
greater than the length of the closure flap hinged to
said first side panel,
weakened lines of separation in said main panel clo-
sure flaps extending along the lines of fold connect-
ing said main panel closure flaps to said main panels
from the ends of these flaps adjacent said first side
wall panel to said registered fold lines.
ends of said main panel closure flaps projecting beyond
the plane of said side wall panel to provide a pro-
jecting tab,
wherein when the portions of said main panel closure
flaps are separated along said weakened lines of
separation, the closure flap secured to said first side
wall is entirely exposed,
said first side wall closure flap being substantially free
of adhesive connection to said main panel closure
flap.

2. The structure of claim 1 and in which at least one
said weakened line of separation include a series of angu-
larly disposed cut scores extending toward the mediate
portions of said main panel closure flaps each said cut
score being connected to an adjacent cut score at one
end, one end of each said cut score terminating closely
adjacent to said lines of fold.

3. The structure of claim 2 and in which said cut scores intermediate their ends are a 100% cut.

4. The structure of claim 2 and in which both said weakened lines of separation are angularly disposed cut scores.

5. The structure of claim 3 and in which said cut scores at said ends adjacent said lines of fold are of greater depth than at said other end.

6. The structure of claim 2 and in which said lines of fold are cut score lines.

7. An outer carton in combination with sticks of a product such as butter and the like including:

a butter carton or the like comprising:

a pair of similar rectangular main panels,

a first side panel hingedly connecting opposed edges of said main panels,

second and third side panels each hingedly connected to the edge of one of said main panels parallel to said opposed edges and folded into face contact to provide a tubular body,

said second side panel lying outwardly of said third side wall panel,

closure flaps hingedly connected to said first and second side wall panels and folded in coplanar relation,

closure flaps on said main panels folded to overlie said side wall closure flaps and secured together in face contact,

registered fold lines extending across said main panel closure flaps normal to the lines of fold connecting said last named closure flaps to said main panels and spaced from said first side panel a distance greater than the length of the closure flap hinged to said first side panel,

weakened lines of separation in said main panel closure flaps extending along the lines of fold connecting said main panel closure flaps to said main panels from the ends of these flaps adjacent said first side wall panel to said registered fold lines,

ends of said main panel closure flaps projecting beyond the plane of said first side wall panel to provide a projecting tab,

separation of said main panel closure flaps along said weakened lines of separation from said main panels defining a product opening,

a plurality of sticks of a product in side by side relation in said carton,

said product sticks arranged with an end of at least one stick registered with said product opening,

whereby said product sticks are adapted to be dispensed through said product opening successively.

8. The combination of claim 7 and in which said product opening is of a length corresponding to the width of at least half said product sticks.

9. The combination of claim 7 and in which at least one said weakened line of separation includes a series of angularly disposed cut scores extending toward the mediate portions of said main panel closure flaps, each said cut score being connected to an adjacent cut score at one end, one end of each said cut score terminating closely adjacent to said lines of fold.

10. A carton blank for use with butter and the like in stick form comprising:

a pair of similar rectangular main panels hingedly connected along parallel fold lines to a first side panel, second and third side panels each hingedly connected to the edge of one of said main panels parallel to said parallel fold lines, closure flaps hingedly connected to said first and second side wall panels, closure flaps on said main panels hingedly connected along parallel fold lines, one pair of said parallel fold lines being a cut score line, corresponding fold lines extending across said main panel closure flaps connected to said main panels along said cut score line, said fold lines being normal to the cut score line and spaced from said first side panel a distance greater than the length of the closure flaps hinged to said first side panel, weakened lines of separation in said main panel closure flaps extending along the cut score line connecting said main panel closure flaps to said main panels from the ends of these flaps adjacent said first side wall panel to said registered fold lines, at least one said weakened line of separation including diagonally extending cut lines having one end adjacent said cut score line, adjacent diagonal lines being connected at one end, ends of said main panel closure flaps extending along the cut score line projecting beyond the fold lines connecting said first side panel to said main panels.
